INVENTOR
Joseph Tarnowski
BY *Julian J. Polanski*
ATTORNEY

UNITED STATES PATENT OFFICE.

JOSEPH TARNOWSKI, OF DETROIT, MICHIGAN.

SLIDING WINDOW.

Application filed April 22, 1926. Serial No. 103,735.

This invention relates generally to windows such as used in houses and the like, the invention having particular reference to a novel type of combination window guard and ventilator.

An object of the invention is the provision of a combination window guard and ventilator of simple construction and novel arrangement of parts.

10 For further comprehension of the invention, and of the objects and advantages thereof, reference will be had to the following description and accompanying drawing, and to the appended claims in which the 15 various novel features of the invention are more particularly set forth.

Fig. 1 of the drawing, is a fragmentary view of the side of a house showing a window embodying my improved combination 20 window guard and ventilator.

Fig. 2 is an enlarged vertical sectional view taken on the line 2—2 of Fig. 1.

Fig. 3 is a similar view taken on the line 3—3 of Fig. 1.

25 The window frame 10, slidably accommodates the lower sash 11 and the upper sash 12. The above mentioned being of common, ordinary construction such as generally used for windows, it being understood that the

30 frame 10, is suitably mounted in the wall 13, of a house, or the like. It being further understood that I do not necessarily limit my invention to the particular type of window as above described, as the said frame 10 may 35 be constructed to slidably accommodate the said sashes 11 and 12 in a horizontal position.

As here embodied my improved window guard and ventilator comprises bars 14 and 40 15, or rods, attached at one extremity, as at 16, and 17, respectively, to the bottom and top of the lower sash 11 and the upper sash 12, respectively, and depending therefrom in a vertical position. It being understood 45 that the wall 13 of the said house, is provided with a suitable aperture or opening to allow the said bars 14 and 15 to enter therein.

The top of the upper sash 12 is provided 50 with a plate having a slideable guide way 20' adapted to slidably support ventilating members 20. The ventilating members are preferably of suitable width to partly close

the opening above the upper sash when said sash is lowered. An upper plate 19' having 55 guide ways therein for accommodating the upper end of said ventilating members is secured to the upper portion of the bars 15 and is carried therewith. These members may be disposed in overlapping relation to uncover a greater portion of the opening or 60 they may be positioned in extended relation it being understood that the ventilating members 20 are slideable laterally of the window on spaced-apart guide ways 20'; knobs 21 being provided as a means of gripping 65 the ventilating members for sliding the same.

It is obvious that I have provided a combination window guard and ventilator, which will prevent children and the like from falling out of the window when the 70 said window is open, and will also permit of ventilating the room, as may be desired.

While I have above described the preferred form, construction and arrangement of the several elements employed, it will be 75 understood that the device is, nevertheless, susceptible of considerable modification therein, and I therefore reserve the privilege of resorting to all such changes as may be fairly embodied within the spirit and scope 80 of the invention as claimed.

Having thus described my invention, what I claim as new and desire to protect by Letters Patent of the United States is as follows:—

1. A combination window guard and ventilator comprising a plurality of spaced bars secured to the upper sash of said window adapted to be between the walls adjacent said window when said upper sash is 90 in a raised position, a plate having spaced guide ways therein mounted on said upper sash, a plate mounted on the upper end of said bars having guide ways therein parallel to the guide ways of said upper sash 95 plate, and ventilating members comprising panel doors slidably guided in said guide way.

2. A combination window guard and ventilator comprising a plurality of spaced bars secured to the upper edge of the upper sash of said window, a plurality of spaced bars secured to the bottom edge of the lower sash of said window, a plate secured to the top

of said upper bars having spaced guide ways therein, a plate secured to the top edge of said upper sash having spaced guide ways therein and adjustable ventilating means comprising panel doors slidably mounted on said upper sash with upper and lower edges disposed in said guide ways, said doors being in spaced relation and adapted to be disposed in overlapped position to uncover the opening above said upper sash when the latter is lowered.

In testimony whereof I have affixed my signature.

JOSEPH TARNOWSKI.
